US0D1036246S

(12) **United States Design Patent** (10) **Patent No.:** **US D1,036,246 S**
(45) **Date of Patent:** **** Jul. 23, 2024**

(54) **CLIP**

(71) Applicant: **The Ridge Wallet LLC**, Santa Monica, CA (US)

(72) Inventor: **Daniel Kane**, Agoura Hills, CA (US)

(73) Assignee: **The Ridge Wallet LLC**, Santa Monica, CA (US)

(**) Term: **15 Years**

(21) Appl. No.: **29/882,878**

(22) Filed: **Jan. 19, 2023**

Related U.S. Application Data

(63) Continuation of application No. 29/813,628, filed on Oct. 29, 2021, which is a continuation of application No. 17/035,261, filed on Sep. 28, 2020, now Pat. No. 11,596,212, which is a continuation of application No. 15/421,596, filed on Feb. 1, 2017, now Pat. No. 10,791,808, which is a continuation-in-part of application No. 14/706,019, filed on May 7, 2015, now abandoned.
